UNITED STATES PATENT OFFICE

122,319

DESIGN FOR A TOBACCO PIPE

Cornelius S. Nicoud, Chicago, Ill.

Application May 27, 1940, Serial No. 92,647

Term of patent 14 years

To all whom it may concern:

Be it known that I, Cornelius S. Nicoud, a citizen of the United States, residing at Chicago, county of Cook and State of Illinois, have invented a new, original, and ornamental Design for a Tobacco Pipe, of which the following is a specification, reference being had to the accompanying drawing, forming a part thereof, in which:

I claim:

The ornamental design for a tobacco pipe, as shown.

CORNELIUS S. NICOUD.
